The ornamental design for a cleaning pad having colored strip, as shown and described.

DESCRIPTION

FIG. 1 is a perspective view of an embodiment of the cleaning pad having colored strip, it should be understood that the stippled surface shading represents a strip of a contrasting color relative to the color of the cleaning pad;

FIG. 2 is a left view thereof;

FIG. 3 is a top view of the cleaning pad having colored strip of FIG. 1;

FIG. 4 is a front view of the cleaning pad having colored strip of FIG. 1, the opposite back view is a mirror image thereto;

FIG. 5 is a right view of the cleaning pad having colored strip of FIG. 1; and,

FIG. 6 is a bottom view of the cleaning pad having colored strip of FIG. 1.

The broken line(s) which define the bounds of the claimed design form no part thereof.
